UNITED STATES PATENT OFFICE.

MILTON B. LOEB, OF NEW YORK, N. Y., ASSIGNOR TO BRILLO MANUFACTURING CO., A CORPORATION OF NEW YORK.

SOAP HOLDER.

Application filed June 17, 1922. Serial No. 569,126.

To all whom it may concern:

Be it known that I, MILTON B. LOEB, a citizen of the United States, and resident of New York city, in the county of Kings 5 and State of New York, have invented a new and useful Improvement in a Soap Holder, of which the following is a specification.

This invention is a holder for a cake of 10 soap, particularly abrasive soap with which an additional abrasive agent, such as steel wool, is used.

Abrasive soap is commonly used for 15 cleaning and polishing metal work, one of the well-known uses being in cleaning aluminum cooking utensils. In such use, steel wool is employed, the wool being rubbed on the soap to take up a small amount of it, and then rubbed on the metal. Due to the 20 abrasive qualities of both the soap and the steel wool, it is desirable to protect the hand of the user by putting the soap in a holder.

However, with a holder—and this is the case with shoe paste and shoe blacking also 25—it is easy enough to get out the soap or paste or blacking from the central, upper part of the cake. But as the cake wears away, it is increasingly difficult to get at the soap or paste in the angles and corners 30 of the box. One of the important advantages attained by this invention is a construction permitting ready access to the soap in the corners and angles of the holder, whereby practically the last particle of the 35 soap may be utilized. To this end, the upper, outer ends of the walls are cut away, which permits the steel wool to get into the angles and corners without difficulty.

The improved holder is provided with 40 holes in the bottom both for drainage, and for insertion of a nail or similar instrument for ejecting residual soap, should there be any.

Other advantages of this invention will 45 appear from the following detailed description and accompanying drawing.

In this drawing, Fig. 1 is a plan view 50 of the preferred form of holder; Fig. 2 is a section on the line 2—2 of Fig. 1; Fig. 3 is a plan view of a modification; Fig. 4 is a section on line 4—4 of Fig. 3; Fig. 5 is a plan view of another modification; and Fig. 6 is a section on the line 6—6 of Fig. 5.

Referring now to this drawing, in which 55 similar reference characters indicate sim-

ilar parts, the bottom of the improved holder is indicated at 5; it is provided with drainage holes 6; straight side walls 7 extend substantially vertically from the bottom, being preferably integral therewith. 60 The side walls may be provided with lugs 8 for engaging with the cake of soap, and holding it in the holder while the soap is in use. The upper, outer ends of the side walls 7 are cut away so that the continuation 9 of the upper edge 10 of a side wall extends substantially to the point 11 at the bottom of the box. Thus the corners of the box are deeply notched with more or less V-shaped notches. 70

This cutting away of the upper, outer ends of the side walls permits the steel wool to get at that portion of the soap in the corners and angles of the holder, so that practically all the soap is utilized, and utilized with no particular difficulty on the part of the user. However, should there be any residual soap left sticking in the corners and angles of the box, a nail may be inserted from below through the drainage holes 6 80 for ejecting it, preparatory to the insertion of a fresh cake of soap. Residual soap may also be readily ejected with a nail or fork inserted in the notched corners of the box. 85

The holder, of course, protects the hand of the user from the abrasive steel wool, and, where the soap is put down on a table, protects the table from the soap. In use, the soap preferably remains in the holder. 90

In the modification shown in Figs. 3 and 4 the bottom 5 is provided with punched out portions 12, each provided with a perforation 13; the perforations 13 act as drainage holes, and permit the insertion of a nail for ejecting residual soap. The portions 12 act as short legs, useful in case the holder is laid down on a wet spot on a table. This form is provided with deeply notched corners as in Fig. 1. 100

In Fig. 5, considerably greater portions of the outer and upper ends of the side walls are cut away, so as to provide a much larger notch at the corners of the box. Here the continuation 14 of the upper edge 10 105 of the box meets the bottom at the point 15, a short distance in from the corner of the box. This construction gives more ready access to the soap, but inasmuch as more soap is exposed, does not protect it so well 110

as it is protected in Fig. 1, with a smaller notch.

Figs. 5 and 6 show additionally outwardly pressed corrugations 16, provided with perforations 17; the outwardly pressed corrugations act as short legs, like the portions 12, Fig. 4; these corrugations furthermore serve as stiffening and strengthening ribs for the bottom portion 5; the holes 17 serve as drainage holes, and for insertion of a nail for ejecting residual soap.

The invention is not limited to the precise construction shown, nor is it necessary to use all the features described. The scope of the invention is indicated in the following claims.

While the invention has been described particularly with reference to an abrasive soap, it should be understood that it may

be used with any kind of soap, as well as with hard salves or pastes, etc.

I claim as my invention:—

A rectangular holder for holding a cake of abrasive or polishing soap while in use, comprising a bottom portion provided with outwardly pressed corrugations, such corrugations forming supports for the holder and serving as stiffening ribs for the bottom portion thereof, the corrugations being apertured for drainage purposes, and vertically disposed side walls extending all the way around the bottom portion, the holder being deeply notched at each corner by the cutting away of adjacent end portions of the side walls down to the bottom of the holder, for permitting access to the soap in the angles and corners thereof.

MILTON B. LOEB.
